PROCESS FOR PRODUCING OLEFINS AND AROMATICS BY THE CATALYTIC CRACKING OF A NAPHTHA

Alfred M. Henke, Springdale, and Robert E. Kline and William C. Offutt, Pittsburgh, Pa., assignors to Gulf Research & Development Company, Pittsburgh, Pa., a corporation of Delaware

Filed Mar. 20, 1964, Ser. No. 353,390
2 Claims. (Cl. 208—120)

This invention relates to the manufacture of olefins and aromatic hydrocarbons, particularly olefins containing about 2 to 5 carbon atoms and aromatic hydrocarbons containing about 6 to 8 carbon atoms.

The conversion of naphthas and/or gasoline into olefins and aromatic hydrocarbons is a process of considerable economic interest, particularly when there is an over supply of gasoline. Such conversion is known in the prior art. However, this known process has suffered from certain weaknesses. One important deficiency is the relatively low ratio of olefins and aromatics formed vs. gases and coke. Thus, these previously known processes give a relatively poor selectivity, forming relatively large amounts of low value materials such as gases and coke and relatively small amounts of the desired more valuable materials, namely olefins and aromatics.

This invention has for its object to provide improved procedure for converting naphtha and/or gasoline into olefins and aromatic hydrocarbons. Another object is to provide improved procedure for converting naphtha and/or gasoline into olefins and aromatics with high selectivity. Another object is to improve the state of the art.

These and other objects are accomplished by our invention which includes contacting a naphtha or gasoline with a silica alumina cracking catalyst at a space velocity above about 4.5 at a pressure between about 0 and 20 p.s.i.g. and at a temperature between about 1000 and 1200° F., the temperature being such as to give a conversion of above about 40 percent at the space velocity and pressure employed. We have found in accordance with our invention that this method of operation results in an unusually high selectivity in regard to formation of olefins and aromatics.

The feed stock employed in our process can be any hydrocarbon mixture which boils predominantly in the range between about 100 and 450° F. Thus, the feed stock may be a straight run naphtha or gasoline, a naphtha or gasoline prepared by catalytic cracking or even a gasoline prepared by reforming in the presence of hydrogen. It will be evident that the feed stock may be primarily naphthenic, primarily aliphatic, primarily aromatic or mixtures of any of these three types of hydrocarbons. We prefer to employ feed stocks which are primarily aliphatic, primarily naphthenic or mixtures of these two types of hydrocarbons. Since the process ordinarily does not result in complete conversion, we contemplate employing as part of the feed stock recycle unconverted hydrocarbons.

The space velocity employed in our process must be above about 4.5 and is preferably between about 6 and 8 liquid volumes of feed stock per volume of catalyst per hour. It will be apparent from data presented herein-after that utilization of space velocities below about 4.5

2

results in much poorer selectivity. While space velocities above about 8 may be employed, we do not include such space velocities as being within the scope of our invention since they are less economical and as will appear from data presented below such higher space velocities do not result in a material improvement in selectivity.

In addition to space velocity, the pressure employed in our process is a vitally important matter. The pressure may be atmospheric pressure or 0 p.s.i.g. On the other hand, pressures up to about 20 p.s.i.g. may be employed in accordance with our invention. Also, slightly reduced pressures such as 600 to 760 mm. of mercury absolute may be employed. There does not appear to be any advantage in using slightly reduced or slightly elevated pressures and we prefer to operate our process at about atmospheric pressure.

The catalyst employed in our process must be an active catalytic cracking catalyst of the silica alumina type. Any such silica alumina cracking catalyst may be employed. While we prefer to employ conventional silica alumina cracking catalyst containing minor amounts of alumina such as about 10 to 25 percent, it is entirely satisfactory to employ other types of silica alumina cracking catalysts such as those having larger amounts of alumina which have been recently developed. Such recently developed catalysts contain between about 30 and 50 percent alumina. The catalyst may be a natural or synthetic silica alumina cracking catalyst. Also, it may be used in the form of a fixed bed or in a moving bed such as is customarily employed in conventional catalytic cracking processes. It should have an Activity Index of between about 25 and 35. When the Activity Index drops below this value, as a result of continued use in the process, the catalyst should be discarded and replaced with fresh catalyst.

The temperature employed in our process is maintained at between about 1000 and 1200° F. and preferably at between about 1050 and 1170° F. The temperature does not have a large or pronounced effect on selectivity. However, it must be adjusted so that a suitable degree of conversion, i.e. above about 40 percent is obtained and preferably between about 50 and 80 percent conversion.

The above-described process is carried out or continued until the catalyst requires regeneration. This is generally indicated by a drop in conversion to below the desired value of about 40 percent. Then the catalyst is regenerated in conventional fashion by combustion. After regeneration the catalyst is again reacted in the process. As will appear from the data presented hereinafter, we have found it advantageous to continue the onstream reaction for a throughput of between about 1 and 8 before regenerating the catalyst.

Regeneration results in reactivation of the catalyst. However, after repeated regeneration the catalyst becomes permanently deactivated and therefore should be replaced.

In the above discussion and in the following example and claims the terms "conversion" and "selectivity" are used. Conversion is defined as being equal to the sum of the following percentage yields (percent by weight of naphtha charged).

Total Percent C₅ and Lighter + Total Percent Net Aromatics + Total Percent Coke.

Selectivity is defined as being equal to:

$$\frac{\text{Total percent C}_2\text{--C}_5\text{ Olefins} + \text{Total percent Net Aromatics}}{\text{Total percent C}_5\text{ and Lighter Gas} + \text{Total percent Net Aromatics} + \text{Total percent Coke}} \times 100$$

Example

In this example the charge stock employed was a straight run Kuwait naphtha having the properties shown in Table I. This stock, prior to use in the experiments constituting this example, was dried and deoxygenated with dry hydrogen to reduce the water and dissolved oxygen contents to below 5 parts per million and 5 milligrams per liter, respectively. The catalyst employed in these experiments was a fixed-bed catalyst composed of a commercial silica alumina cracking catalyst (American Cyanamid Triple A). This catalyst had a mesh size of 10-20. It was dried at 250° F. and calcined at 1000° F. prior to use in the experiments. In these experiments the preheated naphtha was introduced into the bottom of a stainless steel bench scale reactor containing a fixed bed of the catalyst. Vapors of the naphtha feed flowed upwardly through the bed of catalyst and were removed from the upper end of the reactor. The reaction products were cooled and analyzed as indicated hereinafter.

In certain of these experiments the effect of space velocity was determined by employing various space velocities between about 0.5 LHSV and 8.0 LHSV with all other conditions nearly constant. These runs were made in 1-hour cycles. The resulting conversions ranged from 31 to 73 percent by weight of the charge and the resulting selectivities ranged from 46 to 76 percent. The

5

highest selectivity was obtained at 8 LHSV while the lowest was obtained at 0.5 LHSV. The results of these runs, as well as the reaction conditions employed, are given in Table II. It will be noted that Table II also shows the effect of different temperatures.

TABLE II.—Continued

It will be noted from the data presented in Table II that the space velocity has a pronounced effect on selectivity at any given temperature and conversion level. The results of the data presented in Table II are presented in graphical form in FIGURE 1 of the accompanying drawing. Referring to this drawing in which space velocity is shown on the abscissa of the graph and selectivity is shown on the ordinate of the graph, it will be noted that operation between about 4 and 8 space velocity has a very beneficial effect on selectivity. The temperature, however, does not affect selectivity although conversion increases as the temperature increases.

Several runs were also conducted in order to show the beneficial effect of employing a pressure of about atmospheric pressure. Thus, in these runs various pressures between 0 and 200 p.s.i.g. were employed at otherwise constant conditions of 1050° F., 2.0 LHSV utilizing 1-hour cycles. The results of these various pressure runs are given in Table III and are graphically presented in FIGURE 2. In FIGURE 2 percent conversion is plotted against percent selectivity.

puts is not necessary and our invention is not restricted thereto.

What we claim is:

1. A highly selective process for the catalytic conversion of a hydrocarbon feed stock selected from a naphtha-gasoline fraction boiling in the range of between about 100° and 450° F. which comprises contacting said feed stock with a silica alumina cracking catalyst containing about 10 to 50% alumina at a liquid hourly space velocity between about 4.5 and 8, at a pressure between about 600 mm. and 20 p.s.i.g., and at a temperature between about 1000° and 1200° F., thereby producing a high yield of mixed olefinic hydrocarbons having from 2 to 5 carbon atoms and mixed aromatic hydrocarbons having from 6 to 8 carbon atoms and a reduced yield of saturated gaseous hydrocarbons and coke.

2. The process of claim 1 wherein the silica alumina cracking catalyst contains about 10 to 25% alumina, and the process is carried out at a space velocity of between

From the results presented in Table III and in FIGURE 2 of the drawing it will be evident that it is vitally necessary to employ relatively moderate pressures such as 0 to 20 p.s.i.g. if relatively high selectivities such as above about 40 percent are to be obtained.

We have also found that throughput has some effect on selectivity. Thus, the selectivity improves with the length of the on-stream cycle. However, we prefer not to operate beyond a throughput of about 8 between regenerations. While this improvement in selectivity with increasing throughput is relatively minor as compared with the effect of space velocity and pressures, nevertheless we prefer to employ a throughput in the range mentioned and the use of such a throughput is included within the scope of our invention. However, it is to be understood that the use of such moderate through-

about 6 and 8, a pressure between about 0 and 20 p.s.i.g., and a temperature between about 1050 and 1170° F.
